JOHN H. DEAN, OF GRAND RAPIDS, MICHIGAN.

TOBACCO STEMMING AND BOOKING MACHINE.

1,387,244.

Specification of Letters Patent.

Patented Aug. 9, 1921.

Application filed January 13, 1919. Serial No. 270,938.

To all whom it may concern:

Be it known that I, JOHN H. DEAN, a citizen of the United States of America, residing at Grand Rapids, in the county of Kent and State of Michigan, have invented certain new and useful Improvements in Tobacco Stemming and Booking Machines; and I do hereby declare the following to be a full, clear, and exact description of the invention, such as will enable others skilled in the art to which it appertains to make and use the same.

This invention relates to tobacco stripping and booking machines and has for its primary object and purpose the provision of a machine which will strip the stems from the leaves of tobacco and at the same time book the parts of the leaves from which the stems are removed. A further object of the invention is to provide a machine of this character in which the stem of a leaf is fed into the machine and cutting knives brought against the leaf each side of the stem whereby as the leaf is carried into the machine, a severing of the stem therefrom is accomplished, the stem being ejected from the machine and the remainder of the leaf carried around a drum on which it remains, succeeding leaves being booked one over the other on the drum. Various other objects and purposes, including mechanisms for controlling the machine, for stopping the same either automatically or at will, for grasping the end of the stem to positively feed the leaf into the machine, for elevating the front part of the machine for removal of a pack or book of leaves, and for accomplishing many other novel operations not specifically enumerated at this time, will appear as understanding of the invention is had from the following description taken in connection with the accompanying drawings showing a working embodiment of the invention and in which,

Figure 1 is a front elevation of the complete machine.

Fig. 2 is a side elevation thereof.

Fig. 3 is a fragmentary sectional view of the leaf feeding and stem cutting mechanism.

Fig. 4 is a fragmentary transverse section taken through the machine directly in front of the feed wheel thereof.

Fig. 5 is a plan view of the rotary cutting knives.

Fig. 6 is a fragmentary side elevation of

the feed belt, showing that part thereof into which the end of the stem of a leaf is introduced.

Fig. 7 is a fragmentary side elevation showing the operative relations of the various feed and booking belts of the machine.

Fig. 8 is a plan view of a fragmentary detail of the machine.

Fig. 9 is a partial sectional and side view of a part of the control mechanism of the machine.

Fig. 10 is a side elevation of the upper part of the machine, taken from the side opposite to that shown in Fig. 2, and

Fig. 11 is a fragmentary front elevation of details of construction of the machine.

Fig. 12 is an enlarged detail view illustrating the manner of mounting spring leaf holding fingers when the same are employed in a modified form of the invention.

Fig. 13 is a detail front view of the spring leaf holding fingers.

Fig. 14 is a detail vertical sectional view of a portion of a machine equipped with the spring leaf holding fingers shown in Figs. 12 and 13.

Figs. 15 and 16 are detail views illustrating another modification of the invention in which leaf holding and straightening feed rollers are employed.

Like reference characters refer to like parts in the different views of the drawing.

In the construction of the machine, a front table 1 is provided to extend in front of the main supporting parts 3 of the machine which in turn are carried at the upper ends of legs 2, said legs, parts 3, and the table being preferably cast from iron to make a strong support for the mechanism mounted thereon. At opposite sides of the support thus formed, integral posts and forwardly extending webs 4 and 5 extend vertically. A hollow drum 6 is disposed horizontally between said supporting webs, being mounted for rotation, a shaft 112 extending through the same and having rotatable mounts at its ends in suitable bearings as shown in Figs. 2 and 10.

The table 1 has its central portion removed, leaving an opening of substantially rectangular shape in which two plates 69 and 70 are positioned lengthwise of the table, their adjacent edges being spaced apart to make a longitudinal slot between them. A head 7 is removably attached to the table in the opening below the plates

on which certain parts of the mechanism are mounted, being removable as a unit therewith.

A shaft 50 is rotatably mounted in front 5 and above the drum 6 and extends horizontally between the supports 4 and 5. At its middle it carries two wheels or pulleys 10. Adjacent each end near the supports, an arm 46 extends downwardly to a point a short 10 distance above the table 1, being adjustably connected at its lower end to the adjacent support 4 or 5 so that the same may be moved a short distance forward or to the rear. These arms are secured in fixed position 15 by set screws 106. Each at its lower end is formed with an inwardly extending portion 46^a bored to receive a plug 104 which is normally forced a short distance beyond the portion 46^a by spring pressure. The 20 outer ends of plugs 104 are provided with seats to receive the ends of a rod 47 which is located horizontally at the lower end of an arm 9 pivotally mounted at its upper end on the shaft 50. From said lower end of the 25 arm 9 a second arm 8 extends forwardly and upwardly, one of said arms 8 being located at each end of the rod 47. At their front ends arms 8 carry a shaft 97. Wheels or pulleys 12 are rotatably mounted on the rod 30 47, while similar wheels or pulleys 11 are fixed on the shaft 97, one on each side of a grooved wheel 35 also fixed on said shaft 97. Arms 108 are mounted on and extend forwardly from arms 109 and a feed roller 35 which may be constructed of leather, fiber or other suitable material and which is provided at its periphery with spaced notches 15^a, is mounted between the arms 109. The arms 108 project downward at an inclination 40 and extend below the plane of the arms 109 which are approximately horizontal. The lower edge of the feed wheel extends into the slot between plates 69 and 70, while at its upper portion it extends into the 45 groove of the wheel 35, being driven thereby. Extensions 108 are made to the arms 109 in front, the same carrying a small roller 16 for bearing upon the stem of a leaf of tobacco as it is started under the feed wheel. 50 It is apparent that the entire mechanism mounted at the lower end of the arm 9 may be elevated into the dotted line position shown in Fig. 7 or 10 by merely grasping the front portion of the mechanism and pulling hard enough to disconnect the rod 47 from the spring actuated plugs 104 in which the ends of said rod seat; and that thereafter the device may be returned to 55 position by forcing the rod 47 into normal position between said plugs. Furthermore, the position of the feed wheel may be adjusted in a forward or rearward direction by loosening the set screws 106, accomplishing the adjustment and then tightening said 60 set screws.

There is also provided a means for lifting said arm 9 and attached mechanism by the foot of the operator. A link 48 is pivotally attached at its upper end to an arm 50^a which is secured to one end of the shaft 50. 70 Link 48 passes downwardly along the inner side of the support 5 and at its lower end is connected to the rearwardly extending arm 53^a of a bell-crank lever, the downwardly extending arm 53 of which carries a foot 75 member 54 at its lower end by means of which the lever may be operated from full line position to dotted line position as shown in Fig. 10, this acting to elevate the arm 9 and mechanism carried thereby. The weight 80 of said mechanism causes it to return to normal position when the foot member 54 is released and to check too rapid return, a cylinder 51 has a piston working therein the same being connected to the upper end of 85 an arm 52 pivotally mounted at its lower end on one side of the support 5. A link 111 connects the arm 50^a with the piston rod and arm 52 at their pivotal point of connection and extends a short distance to the rear 90 to normally strike against a stop 110 adjustably mounted below the cylinder 51. A check is thus interposed against rapid descent of the arm 9 and attached mechanism, and a stop made to govern the exact position 95 taken when the parts of the mechanism carried by the arm 9 are in lower position. The two belts which pass around the pulleys 10, 11 and 12 lift with the elevation of pulleys 11 and 12, and a suitable retaining roller 107 100 may be used to hold the belts against the pulleys 10 when the other pulleys are elevated as shown in Fig. 10.

The belts B pass over pulleys 10, thence to the rear over tensioning rollers 14 mounted in front of rollers 13 and carried on arms 34 as shown in Fig. 2. Belts B pass over and back of the rollers 13 thence downwardly under idle rollers 21 carried at the ends of arms 22 pivotally mounted on a rod 26 on the supporting frame of the machine, thence under the table and under idle rollers 18 at the front of the machine and upwardly over upper idle rollers 17 and then back over the table, passing one at each side of the slot 115 between plates 69 and 70, and under and around the drum 6, thence around the pulleys 12 and 11, this completing the circuit of the belts. The arms 22 and 34 serve in the capacity of belt tensioners, it being designed that the same may be operated by springs. Drum 6 is driven by the belts. 120

Two other belts A pass around rollers 17, 18, 21 and 13, thence under the drum 6, being located outside of the belts B and driven in unison therewith. Said belts A and B are of sufficient width to carry as large a leaf of tobacco as the machine will strip when the same is spread over the belts. 125

Directly under the feed wheel and passing 130

through the head 7 is a narrow belt 73 of leather in which a plurality of notches 73^a are cut as shown in Fig. 3. The belt is cut at its upper portion at each side at an angle 5 and is provided with a central upper groove 73^b as shown in Fig. 6, this construction precluding interference of the belt with the cutting knives, hereafter described, and aiding in receiving the stem of the leaf of 10 tobacco fed into the machine. This belt passes around a driving roller 101, fixed on a shaft 100, thence downwardly and forwardly under a tension roller 86 carried at the lower end of a depending pivotally 15 mounted arm 90, thence upwardly over a roller 87 suitably mounted on a projecting part 88 of the main support, and thence to the rear through the head 7. The belt 73 is pressed upwardly against the feed wheel 20 15 by a roller 76 over which it passes. Roller 76 is fixed on a short shaft or pin 77 at the rear end of a lever 78 pivotally mounted between its ends at 103 on the head 7 and actuated by spring 85 to press roller 76 25 against the belt 73. It is evident that with this construction, the stem of a leaf of tobacco, when entered under the roller 16 down the inclined groove 89 made in the upper side of the head 7 in front of the 30 roller, will, when the belt 73 comes to such position that the end of the stem may enter a notch 73^a, be drawn under the roller 16 and thence under the feed wheel 15, the stem passing under the slot between the plates 35 69 and 70 while the sides of the leaf spread over the carrying belts A and B. This has the effect to tension or stretch the leaf at each side of the stem as it passes under the wheels 16 and 15 and renders the same particularly 40 easy to cut at such tensioned parts when brought into contact with a rotary cutting knife, as will now be described.

The knives 74 and 75 are of circular form and are located below the plates 70 and 69, 45 respectively on opposite sides of the slot between the plates. One knife 74 is located in a plane slightly below the other knife 75 and is oppositely beveled as shown. Said knives are fixed at the upper ends of vertical shafts 94 and 93 which are rotatably 50 mounted at the rear ends of brackets 67 pivotally mounted on the under side of the head 7 in spaced apart relation, one at each side of the slot between plates 69 and 70. Each bracket is pivotally mounted between 55 its ends on a vertical shaft 82, which passes upwardly through one end of a cross bar 68 disposed below brackets and extends across the space between the same, and 60 each vertical shaft 82 passes through its bracket and connects with the head 7. A coiled spring 79 under compression is disposed between the front ends of the brackets 67, the tendency being to bring the rear 65 ends of the brackets together, which tendency is controlled by an adjusting screw 81 threaded upwardly through bar 68 and provided with a beveled head to contact with associated beveled lugs projecting from the brackets 67 back of their pivotal mounts 70 as shown in Fig. 4, this adjusting the brackets and the knives 74 and 75 to any desired position with respect to each other. A locking washer 80 is used with adjusting screw 81 to keep it in any position to which it may be adjusted.

Directly in front of the knives 74 and 75 are located two fingers 72, pivotally mounted on the head 7 under the plates 69 and 70, on the pins 102. One of these fingers is located at each side of the slot, its forward end being beveled on its under side and its rear end on its upper side, and drawn normally across the slot by springs 95 and 96. The stem of the leaf 85 of tobacco passes under the inner edges of said fingers 72, the leaf at points adjacent the stem passing with the belts 4 and 5 over said fingers and the adjacent head 7 to which they are attached, this aiding in stretching the leaf at the stem for easy cutting all of the tobacco of any value from the stem, it being apparent that the oppositely beveled circular knives sever the stem from the leaf, the stem being delivered into an outlet tube 95 91 at the back of the head 7, being guided therein from the knives under the part 92 of the head 7, as shown in Fig. 3.

A shaft 32 is mounted vertically in the rear part of the support, having suitable 100 bearings as shown at 60 on the support, and drives the upper shaft on which rollers 13 are mounted, through suitable gearing. At an intermediate point in its length, it has connection by means of beveled gears 33 105 with a horizontal shaft 20, mounted on the support and extending forward to drive the shaft 100 through gearing shown. Shaft 100 carries spiral gears 98, meshing with spiral gears 99 on the vertical shafts 93 and 110 94 on which the knives 74 and 75 are fixed to drive the same, gears 98 having suitable guards and oil pockets 84 into which the lower parts of the gears extend.

An electric motor 65 is located adjacent 115 the left hand side of the support, having connection with a shaft 66 through a universal joint connection shown at 62, 63 and 64 in Fig. 8. Shaft 66 is rotatably mounted on and under a swinging arm 61 located horizontally substantially in alignment with the motor shaft, and the shaft 66 at its free end carries a spiral gear 30 adapted to mesh with a similar gear 31 on the lower end of the vertical shaft 32. When the motor is in 120 operation and the gears 30 and 31 in engagement, the mechanism is operated, belts A, B, and 73 being driven, drum 6 rotated, and the knives 74 and 75 driven as will be evident.

A foot lever 28 is pivotally mounted at its upper end at 55 on a side of the main support of the machine. A short distance below its upper end it is connected to an 5 irregularly shaped member 56, which extends upwardly above the upper end of lever 28 and has an extension bar 36 thereto which reaches to the end of the drum 6, being provided with a roller 37 to ride on the inner 10 surface of the drum and with every revolution of the drum ride over a cam 38 fixed on the inner side of the drum in position to pass under the roller. A dog 58 is pivotally mounted at the rear of the member 15 56 and is normally elevated by spring 58^a above a lug 57 attached at the side of a bar 27 movably mounted alongside the member 56 and having pivotal connection at 59 with the swinging arm 61 heretofore described. 20 A spring 41 on rod 44 positioned below bar 27 and disposed between a stationary stop 42 and a downwardly projecting part of said bar 27 normally moves the bar forwardly to disengage gear 30 from gear 31. A second 25 spring 39 acts on a projection 56^a of the member 56 to force the roller 37 against the inner side of the drum 6. Spring 39 is adjustable as to tension through adjustment of the block 39^a on the rod 44, against which 30 block one end of the spring bears. This is a valuable feature of the invention as the pressure of the roller 37 against the inner side of the drum and against the cam projection 38 may be regulated so as to stop the 35 drum always at substantially the same point. At the lower end of a foot lever 28 a foot piece 43 is pivotally mounted and a rod 29 is connected at its upper end to the dog 58 and at its lower end by a pin and slot connection to the foot piece at a point back of 40 the connection of the foot piece to lever 28. 45 By pressing downwardly on the rear end of the foot piece 43 and then forcing the lower end of the foot lever 28 to the rear, bar 27 is moved rearwardly and a driving engagement made between gears 30 and 31, this serving to drive the machine. The 50 operation of the mechanism of the machine may be controlled readily by the foot of the operator and a continuous or an intermittent operation had, and even though the foot lever be moved in a rearward direction, whenever the cam 38 comes under roller 37, there is an action relieving dog 58 from 55 engagement with the lug 57, causing the mechanism to be automatically disconnected from the driving gear 31.

In operation, with the drum in the position shown in Fig. 9, that is, with the roller 60 37 on the cam 38, the machine is in position to take the but end of a stem of a leaf of tobacco, the notches 73^a in belt 73 helping in this connection. The belt 73 may also be given a downward movement under pressure of the stem under the feed wheel, roller

76 yielding when pressure is applied. The machine is started by operating the foot lever 28 and attached foot piece 43, and the stem is guided into the slot between plates 69 and 70 and under the guide fingers 72 70 and knives 74 and 75, being fed by the feed wheel 15 and belt 73 to the knives. The operation of the machine may be more or less continuous depending upon the skill of the operator. As the feeding of the leaf progresses, the thickest part of the stem is cut away from the leaf until such time as the stem becomes of small size and need not be cut away, the knives thereupon cutting through the stem and permitting the leaf to 75 pass under belts B around the drum 6. The stem is ejected through the tube or chute 91, and the drum automatically stops with the leaf on its upper side under the belts B. The operation may be indefinitely repeated and 80 as the leaves are entered into the machine at substantially the same point, that is, started into the machine with the drum occupying the same relative position, the leaves with the stems remove accumulated 85 one over the other on the drum until such time as they are to be removed in a pack or book, this being done as previously described, by operating the lever 53 to elevate the arm 9 and attached mechanism. 90

There are various adjustments and refinements in the mechanism for more successfully operating the same. For instance, arms 8 and 9 may be adjusted with respect to each other and held in position by the turn buckle adjustment shown at 45. The tension of the belts A and B is a yielding spring tension, springs 25 around rod 26 acting on the arms 22, as shown in Fig. 1, and the same or equivalent spring devices 105 may be used to elevate arms 34. To cause the leaves of tobacco, when around the drum, to remain in close contact therewith, I have provided a plurality of curved spring metal fingers 113 to fit against the drum 6 on the 110 lower front portion thereof, the same being attached to shoes 114 pivotally mounted on a rod 115, which rod is mounted at the upper ends of arms 116 which in turn are mounted on a shaft 117 pivotally mounted 115 at the rear end of and between two brackets 118 fixed to and above the table 1 in front of the drum. An arm 119 having a spring 120 acting thereon is attached either to the shaft 117 or formed integral with arm 116, 120 there being a normal tendency for this construction to bring the fingers 113 against the surface of the drum and thus hold the leaves of tobacco against the drum at the front lower portion thereof where belts B 125 do not contact with the drum. Otherwise the lower edges of the leaves drop vertically and strike against the table bending and crumpling at their lower edges when the drum is rotated to receive succeeding leaves. 130

The spring 120 is secured at one end to a lug 118^a depending from and preferably formed integral with the bracket 118 and arranged in substantial parallelism with the 5 arm 119 to which the said spring 120 is adjustably connected.

The arms 116 and associated retaining fingers 113 may be drawn to the rear at any time when arms 8 and 9 and attached mechanism 10 is elevated to remove the book of leaves of tobacco from the drum.

Two rods 121 are mounted one at each end of the drum and in front thereof, being carried by supporting brackets 122 as shown.

15 A member 123 is adjustably mounted to move lengthwise of each rod and to turn about the axis of the rod, and to each member 123 a rod 124 is pivotally mounted at 125, each rod 124 serving as a shaft on 20 which rollers 126 may turn. The pivotal mounting of the rod 124 on the pivoted member 123 not only permits a horizontal movement or adjustment of the roller on 25 the pivot 125 but it also enables the roller 126 after being swung outward laterally of the machine as illustrated in dotted lines in Fig. 16 of the drawings to be swung downward in a direction longitudinally of the machine to arrange it in a lowered position 30 upon the support or table 1. The rollers 126 extend toward each other, their adjacent ends lying one at each side of the feed wheel 15, and as a leaf of tobacco is spread out and fed into the machine, said rollers 35 press against the same and hold it from contracting and getting out of shape as the operation of stemming proceeds. The rollers by their weight practically smooth the leaves so that when brought to the drum 6 40 with the stems removed, they book thereon in smooth and even order. At any time desired the same may be turned about the rods 121 into the dotted line positions shown in Fig. 16, and they also may be adjusted 45 to any desired or proper position by moving the same lengthwise of said rods 121.

I claim:

1. A tobacco stemming machine comprising a support, a table having a longitudinal 50 slot therein carried by the support, conveying means leading over the table to carry a leaf in the direction of the length of the stem thereof over the table, a belt mounted directly below the slot in the table, 55 means to move the belt in the same direction as said conveying means, means to press the stem of the leaf against the belt, and cutting means located between the belt and the upper surface of the table for severing the stem 60 from the leaf, substantially as described.

2. A tobacco stemming machine, a table having a slot therein, an endless belt mounted below the slot, means for forcing the stem 65 of a leaf of tobacco against the belt thereby bringing the stem below the plane of the

upper side of the table, a rotary knife mounted to turn on substantially a vertical axis at each side of the slot and below the table but above the belt, means to drive the belt to carry the stem to the rear of the 70 table, means to carry the remainder of the leaf over the table in the same direction, and means to rotate the knives to sever the stem progressively from the leaf, substantially as described. 75

3. A tobacco stemming machine comprising a table having a slot therein, an endless belt mounted below the slot, means for driving the belt to the rear of the table, means for carrying a leaf of tobacco over 80 the table from front to rear, a drum back of and above the table with which said leaf carrying means engages to drive the drum and deliver the leaves from the table to the drum, and means to sever the stem from 85 each leaf as it passes over the table and prior to its delivery to the drum.

4. A tobacco stemming machine comprising a table having a slot therein, an endless belt mounted below the slot, means to press 90 the stems of leaves of tobacco against the belt, cutting means located directly over the belt to sever the stem from the leaf, a drum rotatably mounted above and at the rear of the table, means to carry leaves of tobacco 95 one at a time over the table, said means engaging with the drum to rotate the same, driving means for the belt and leaf carrying means, and means operated by the drum with each revolution thereof acting to automatically disconnect said driving means, 100 substantially as described.

5. A tobacco stemming machine comprising a table and a drum rotatably mounted above and back of the table, a support for 105 carrying the drum and table, a rod carried by the support above and at the front of the drum, pulleys on the rod, an arm on the rod extending downwardly in front of the drum, a shaft carried at the lower end of the arm, 110 pulleys mounted thereon, a second arm extending from the lower end of the first arm and mounted on said shaft, a pulley mounted at the front end of the second arm, belts leading from the front of the table to the 115 rear under back of and over the drum and thence around the pulleys at the lower end of the first arm and at the front end of the second arm, thence back over the pulleys on the rod to the rear of the support, thence downwardly and under the table, a second arm connected to the rod, a bell crank pivotally mounted on the support, the lower portion of which is provided with a foot 120 engaging member, and a link connecting the said second arm with the upper portion of the bell crank lever, substantially as described. 125

6. A tobacco stemming machine comprising a support, a table carried by the support, 130

a drum rotatably mounted above and back of the table on the support, carrying means for carrying leaves of tobacco one at a time over the table and delivering the same to the 5 drum with the successive leaves in superposed relation to each other on the drum, said carrying means engaging with the drum to rotate it, a cam projection on the inner side of the drum, a motor carried by the support 10 port, a shaft driven thereby, a second shaft rotatably mounted on the support, gears on the two shafts adapted to be engaged, means for severing or cutting the stems from the leaves of tobacco as they pass over the table, 15 means to drive the cutting means and the carrying means from the second shaft, a slidably mounted member connected to the motor shaft and mounted on the support, a spring associated therewith tending to disconnect the gears on the two shafts, a lever pivotally mounted on the support and extending downwardly therefrom, an irregularly shaped member connected to the upper 20 end of the lever adjacent the slidably mounted member and having an extension reaching to the drum, a roller on the upper end of the extension riding on the inner side of the drum and over the cam projection once with each revolution of the drum, a spring 25 acting on said irregularly shaped member for holding the roller against the drum, means for adjusting the tension of the spring, a dog pivotally mounted on the irregularly shaped member, a lug on the 30 slidably mounted member behind which the dog may be positioned, means mounted on the lower end of the lever and connected with the dog for moving it behind the lug, and spring means for normally raising the 35 dog above the lug, substantially as described. 40

7. A tobacco stemming machine comprising a support, a table having a longitudinal slot therein carried by the support, conveying 45 means leading over the table to carry a leaf in the direction of the length of the stem thereof over the table, a belt mounted directly below the slot in the table, said belt having a plurality of spaced apart notches 50 in the upper side thereof, means to move the belt in the same direction as said conveying means, means to press the stem of the leaf against said belt, the end of the stem being adapted to enter a notch in the belt, and 55 cutting means located between the belt and the upper surface of the table for severing the stem from the leaf.

8. A tobacco stemming machine comprising a support, a table having a longitudinal slot therein carried by the support, conveying 60 means leading over the table to carry a leaf of tobacco in the direction of the length of the stem thereof over the table, a belt mounted directly below the slot in the table, said belt at its outer side having a plurality of spaced apart notches cut therein and having 65 portions cut at an angle from the belt whereby the outer side of the belt has two angularly disposed portions leading downwardly and away from each other, said belt 70 also being formed with a groove at the meeting edges of said angularly disposed portions, means to move the belt in the same direction as said conveying means, means to press the stem of the leaf against the belt 75 at said grooved and notched portions thereof, and cutting means located between the belt and upper surface of the table for severing the stem from the leaf as it is carried into the machine, substantially as described. 80

9. A tobacco stemming machine comprising a support, a table having a horizontal slot and carried by the support, conveying means leading over the table to carry a leaf in the direction of the length of the stem 85 thereof over the table, a belt mounted directly below the slot in the table, said belt having a plurality of spaced notches, means to move the belt in the same direction as the said conveying means, means to press the stem of the leaf against said belt to cause 90 the said stem to enter a notch of the said belt and cutting mechanism for severing the stem from the leaf.

10. A tobacco stemming machine comprising a support, a table having a longitudinal slot and carried by the support, conveying means leading over the table to carry a leaf in the direction of the length of the stem thereof over the table, a belt mounted directly below the slot in the table, said belt 100 at its outer side having a plurality of spaced notches and having portions cut at an angle from the belt whereby the outer side of the belt has two angularly disposed portions 105 leading downwardly and away from each other, said belt being also formed with a groove at the meeting edges of the said angularly disposed portions, means to press the stem of the leaf against the belt at said 110 grooved and notched portions and cutting means for severing the stem from the leaf.

In testimony whereof I affix my signature.
JOHN H. DEAN.
